UNITED STATES PATENT OFFICE.

CHARLES WARD HALL, OF LARCHMONT, NEW YORK.

AEROPLANE.

1,287,297.

Specification of Letters Patent. Patented Dec. 10, 1918.

Application filed May 19, 1917. Serial No. 169,640.

To all whom it may concern:

Be it known that I, CHARLES WARD HALL, a citizen of the United States, and a resident of Larchmont, in the county of Westchester 5 and State of New York, have invented certain new and useful Improvements in Aeroplanes, of which the following is a specification.

My invention relates to aeroplanes and, 10 having for its object the improvement of the means for their control, comprises certain novel features of form, arrangement, and combination of parts as hereinafter described and more particularly pointed out 15 in the appended claims.

One specific embodiment of my invention as applied to a biplane of common type is shown by way of illustration in the accompanying drawings, in which—

20 Figure 1 is a perspective view of a machine equipped with my improved control or stabilizing fins; Fig. 2, a similar view, enlarged, of one end of the upper plane, with a part of its upper surface covering broken 25 away, and of the control fin mounted thereon; Fig. 3, a broken detail showing in section, on the line 3 3 of Fig. 4, a control fin and in plan certain parts of the framework 30 of the main upper plane and the operative 35 connections of the fin; Fig. 4, a similar detail showing partly in section and partly in rear elevation the parts shown in Fig. 3; Fig. 5, a view partly in section and partly in elevation on the line 5 5 of Fig. 4; Fig. 6, a side view, and Fig. 7, a front view, 40 partly in elevation and partly in section, of the control mechanism mounted within the cock-pit of the machine and operatively connected with the control fins; and Figs. 8 and 45 9, details partly in vertical section and in perspective, respectively, of different parts of the mechanism shown in Figs. 6 and 7.

The same reference characters indicate like parts throughout the several figures of 45 the drawings.

The machine here illustrated has, for its principal parts, a body or fuselage B, carrying the usual rear elevating planes and vertical rudder, and upper and lower supporting planes or wings W W', which are framed and covered above and below in the usual or in any suitable manner.

For the control of the machine I have provided, in addition to the elevating planes and 55 rudder, vertical control or stabilizing fins 1 which are movably and preferably adjust-

ably mounted on opposite sides of the machine above the upper supporting plane and adjacent to its outer ends and are, or may be, automatic in their action.

Each of these stabilizing fins, that on the right of the machine for example, is pivotally mounted upon a fixed vertical post 2, secured to the framework of the upper plane in any suitable way or formed by an upward 60 extension of one of the rear wings supporting struts 3, which bears in an elongated slot 4 cut through the fin and extending rearwardly from a point approximately at its longitudinal center. A movable post 5, 65 bearing in a similar slot 6 in the forward end of the fin, extends down through a suitably elongated opening in the upper surface covering of the plane and is mounted to slide transversely of the machine upon two 70 arms 7 by means of grooved rollers 8 which are pivoted to the downturned outer ends of the arms and travel in slots 9 in a guide-piece 10 secured at its ends to two ribs 11 of the plane. A horizontal brace rod 12, 75 which is pivoted at 13 to the post and slides in a groove 14 formed in the lower part of the fin, serves to hold this post in an upright position within the slot in the fin.

A rod 15, which extends nearly from end 80 to end of the plane between its upper and lower surface coverings through openings provided therefor in the ribs, is mounted to slide and to rotate in bearings formed in brackets 16 fixed to the rear side of the forward spar 17 of the plane. One end of this rod passes through suitable openings in the downturned ends of the carrier arms 7 to one of which it is secured by bosses 18. A spur-wheel 19, fixed upon the rod, is geared 85 to a second spur-wheel 20, which is pivoted within a slot 21 in the post 5 and is in turn geared to a rack 22 fixed to the stabilizing fin within its forward slot. The stabilizing fin on the left of the machine is mounted 90 similarly to that already described and is connected in the same way to the other end of the rod 15.

At the center of the rod 15, over the body 95 of the machine, is a sleeve 23 which is free to turn upon the rod but is held in position longitudinally thereof by two fixed bosses 24 between which it is mounted. To a stud 25 carried by this sleeve are attached the ends of two cords 26, which pass over guide-sheaves 27 mounted upon the spar 17 and down through openings in the lower surface 100 105 110

covering of the plane to the cock-pit in the body, where, after passing over guide-sheaves 28 suitably mounted therein, they are connected to control mechanism shown, in 5 the form preferred, in Figs. 6 and 7.

This control mechanism consists of a shaft 29 which is journaled in brackets 30 attached to the bottom of the body of the machine and carries a post or lever-arm 31 by which 10 it is rocked by the pilot to rotate the grooved pulleys 32 and through the cords 33 to control (by connections not shown) the elevating planes of the machine in the usual manner. Two hollow guide-posts 34, slotted 15 along their sides, are supported between brackets 35 carried by the swinging post and surrounding each is a tension spring 36 which is attached at its lower end to the grooved flange of a threaded sleeve 37 adjustably mounted on the threaded lower end 20 of the guide-post and at its upper end to the flanged sleeve 38 sliding upon the guide-post. Within each guide-post slides a cross-head 39 provided with laterally projecting ears 40 which extend outwardly through the slots 25 in the sides of the guide-post and are adapted to bear against the lower end of the sleeve 38; and to these two cross-heads are respectively attached the lower ends of the cords 30 26, passed over guide-sheaves 41 mounted on the offset middle portion of the shaft 29, and the ends of a chain 42 which passes over the sprocket-wheel 43 fixed on one end of a shaft 44 journaled in a cross-head at the upper end 35 of the swinging post and carrying on its other end a hand-wheel 45. A dog 46, which is pivoted to the hand-wheel, is adapted to engage at one end in a slot 47 in the cross-head on the swinging post to lock the wheel, 40 and through it the stabilizing fins, against movement, whenever the wheel is turned so as to bring the fins into a position parallel to the longitudinal axis of the machine, and the dog is either pressed toward or held out 45 of such locking engagement with the slot by a spring 48.

Near the center of the rod 15, and also 50 over or just to one side of the body of the machine, is a worm gear 50 which is keyed to the rod to rotate therewith between two of the bearing brackets 16 but through which the rod is free to slide; and, meshing with this gear, is a worm 51 on the upper end of a shaft 52 which, journaled in suitable bearings 55 attached to the framework of the machine, extends downward, preferably immediately behind and inclosed within a stream line cover (not shown) of one of the wing supporting struts, so as to bring the handwheel 53 fixed to its lower end within 60 easy reach of the pilot.

The operation of the stabilizing fins is as follows: When the control-wheel 45 is locked the fins are held immovable in a position 65 parallel to the longitudinal axis of

the machine and function as bilge keels or box kite sides in the same way as do the usual fixed fins in common use. When, however, the control-wheel is unlocked, the fins are movable about the posts on which 70 they are pivoted and are automatic in their action, or may, if desired, be controlled or actuated by the pilot. The pilot is able to adjust the fore and aft position of the fins by turning the hand-wheel 53, which causes 75 the rod 15 to rotate and through the spur-wheels 19 and 20 and rack 22 moves the fins forward or backward, to the limit permitted by the length of the slots 6, and the worm holds them locked in any position to which 80 they have been moved. When the fins are at their extreme forward position, the moment-arm between the pivot posts 2 and the center of pressure of the fins is at its maximum and automatic control is most sensitive, 85 and, as a given side pressure will then, having the longest possible leverage on which to act, cause the greatest deflection or incidence of the fins, the restoring movement is also the most powerful; while at their extreme backward position the pivot posts are 90 approximately at the longitudinal center of the fins and automatic control practically ceases. The pilot will accordingly adjust the fins to such intermediate position as will 95 give just the degree of automatic control which he prefers or which is indicated for the weather conditions at the time. Then, on the side slipping of the machine or a veering or hauling of the relative wind, a 100 pressure is exerted upon one side or the other of the fins and causes them to swing together to the right or left as the case may be, incidentally forcing the rod 15 through its connection with the posts 5 to slide and 105 stretch one or the other of the springs 36 and rotating the control wheel 45. The fins are thus automatically caused to present an angle of incidence to the line of travel of 110 the machine which effects a righting force approximately proportional to the disturbance by reason of four simultaneous reactions—one by inertia about the longitudinal axis of the machine through the vertical 115 moment arm between its center of gravity and the center of pressure or of lateral resistance of the fins, another similar reaction through the vertical moment arm between the center of pressure of the body and the center of pressure of the fins, a turning or yawing moment about a vertical axis of the machine through the moment arm between the rudder and the control fins, and a side slip opposite in direction to the side 120 slip due to the original loss of balance—causing the supporting planes on the lower side of the machine to travel faster and consequently to exert a greater lift than on the high side of the machine; all of which right- 125 130

ing forces immediately cease as their cause, the side pressure produced by the original side slip or the veering or hauling of the relative wind, ceases upon the restoration of 5 the machine to a condition of lateral balance. The springs 36 serve both to damp the swinging movement of the fins, which is limited by the transverse movement permitted the movable post 5 or by the movement 10 of the sleeves 38 upon the guide-posts or both, and to restore the fins at once to their normal neutral position as soon as the machine recovers its balance, thus preventing shock and assuring a steady easy recovery.

15 Similarly, when the pilot desires to give the machine a position other than normal, he turns the control wheel 45 so as to cause the control fins to meet the relative wind at the necessary angle of incidence and 20 thereby tips or banks the machine through the reactions above described. In either case the reactions of the fins may be accelerated or retarded by a suitable use of the rudder.

25 While I have shown and described, by way of illustration, the construction which I prefer and which I now consider to be the best mode for applying the principle of my invention, it will be understood that such 30 construction may be greatly modified in its several parts, or equivalents substituted therefor, and that certain features may be omitted entirely, without departing from the spirit or sacrificing the advantages 35 thereof. For example, the stabilizing fins may in a biplane or multiplane machine be placed just below instead of above one or more of the upper wing planes or may be divided by the wing surface so as to be 40 partly above and partly below it; a single stabilizing fin, centrally mounted, may be used instead of two or more fins symmetrically disposed on opposite sides of the machine; and the fore and aft adjustability 45 of the fins may be omitted and their action can, if desired, be made automatic only, in which case the construction can be simplified in obvious ways.

The word "plane" as used herein is to be 50 understood as including any suitable curved or warped surface, and by the term "vertical" a true normal is not intended but any angle approximate thereto.

What I claim as new, and desire to secure 55 by Letters Patent, is—

1. The combination with an aeroplane of a partially balanced automatic auxiliary plane which is mounted to swing by the action thereon of the relative wind to a limited extent about an axis positioned between its fore and aft center of pressure and its rear end.

2. The combination with an aeroplane of an automatically operative auxiliary plane 65 which is mounted to swing to a limited ex-

tent about an axis behind its fore and aft center of pressure and adjustable with respect thereto.

3. The combination with an aeroplane of a vertically disposed auxiliary plane which is yieldingly held in normal position parallel to the longitudinal axis of the aeroplane and so mounted as to automatically swing by pressure of the relative wind about an axis between its fore and aft center of pressure 75 and its rear end to an angular position with respect to said longitudinal axis.

4. The combination with an aeroplane of a vertically disposed auxiliary plane which is yieldingly held in normal position parallel 80 to the longitudinal axis of the aeroplane and so mounted as to automatically swing by pressure of the relative wind to a limited extent about an axis adjustable to and back from its fore and aft center of pressure. 85

5. The combination with an aeroplane of a vertically disposed auxiliary plane which is pivotally mounted behind its fore and aft center of pressure and yieldingly held in normal position parallel to the longitudinal 90 axis of the aeroplane and means for manually controlling the angular position of the plane.

6. The combination with an aeroplane of a vertically disposed auxiliary plane which is yieldingly held in normal position parallel 95 to the longitudinal axis of the aeroplane and is mounted to automatically swing by pressure of the relative wind about an axis behind its fore and aft center of pressure and adjustable to and from said center of pressure and means for manually controlling the adjustment of its pivotal axis to regulate the automatic action of the plane. 100

7. The combination with an aeroplane of a vertically disposed auxiliary plane which is yieldingly held in normal position parallel to the longitudinal axis of the aeroplane and is mounted to swing about a pivotal axis behind its fore and aft center of pressure and adjustable with respect thereto and means for manually controlling both the position of the pivotal axis and the angular position of the plane. 110

8. The combination with an aeroplane of a vertically disposed auxiliary plane automatically operative on a lateral tilting of the aeroplane about its longitudinal axis to assume a position presenting an angle of incidence adapted to effect a righting moment, means for yieldingly holding said auxiliary plane in neutral position parallel to the longitudinal axis of the aeroplane and automatically operative to return it to such position as the aeroplane is restored to lateral balance, and means whereby the pilot within the body of the aeroplane may both control and effect the movement of said auxiliary plane. 115

9. The combination with an aeroplane of 120

- 5 a stabilizing fin mounted upon a supporting plane of the aeroplane to swing about an axis substantially perpendicular to the supporting plane and behind the longitudinal center 5 of the fin and means for yieldingly holding the fin in normal position parallel to the longitudinal axis of the aeroplane.
10. The combination with an aeroplane of a stabilizing fin mounted upon a supporting plane of the aeroplane to swing about an axis substantially perpendicular to the supporting plane and behind the longitudinal center of the fin, means tending normally to hold the fin in position parallel to the longitudinal axis of the aeroplane, and means 10 for limiting the swinging movement of the fin.
- 15 11. The combination with an aeroplane of a stabilizing fin mounted upon a supporting plane to swing about an axis substantially perpendicular to the supporting plane, and means within the control of the pilot for adjusting the fore and aft position of the fin with respect to its pivotal axis.
- 20 12. The combination with an aeroplane of a stabilizing fin mounted upon a supporting plane of the aeroplane to swing about an axis substantially perpendicular to the supporting plane, means for adjusting the position of the fin with reference to its pivotal axis, and means operable by the pilot for controlling and effecting the movement of the fin about such axis.
- 25 13. The combination with an aeroplane of a plurality of stabilizing fins mounted symmetrically on opposite sides of the aeroplane upon one of its supporting planes and connected to swing together each about a pivotal bearing behind its longitudinal center and substantially perpendicular to the supporting plane, means tending normally to hold the stabilizing fins in position parallel to the longitudinal axis of the aeroplane, and means within the control of the pilot for adjusting the fore and aft position of the fins with respect to their pivotal bearings. 40
- 30 14. The combination with an aeroplane of a plurality of stabilizing fins mounted symmetrically on opposite sides of the aeroplane upon one of its supporting planes and connected to swing together each about an axis behind its longitudinal center and substantially perpendicular to the supporting plane, and means operable by the pilot for both 45 controlling and effecting the movement of the fins.
- 35 15. In combination with an aeroplane, a plurality of stabilizing fins mounted symmetrically on opposite sides of the aeroplane to swing each about a pivotal bearing behind its longitudinal center and substantially perpendicular to the supporting plane of the aeroplane, means tending normally to hold the fins in position parallel to the longitudinal axis of the aeroplane, means operable by the pilot for adjusting the fore and aft position of the fins with respect to their pivotal bearings, and means operable by the pilot for both controlling and effecting the movement of the fins. 50 55 60 65 70

CHARLES WARD HALL.
